(57) **CLAIM**

The ornamental design for a pilot multipurpose cursor control unit for vibrations environment, as shown and described.

DESCRIPTION

FIG. 1 is a front, left and top perspective view of a pilot multipurpose cursor control unit for vibrations environment showing our new design;

FIG. 2 is a partial back, left and top perspective view thereof;

FIG. 3 is a back, left and top perspective view thereof;

FIG. 4 is a top view thereof; and,

FIG. 5 is a back, right and top perspective view thereof.
